Application June 19, 1943, Serial No. 491,438

19 Claims. (Cl. 315—205)

1

This application relates to electron tube circuits and is a continuation-in-part of my application Serial No. 314,767, filed January 20, 1940.

A general object of the invention is the provision of a novel method and means to change the distribution of electrical effects in a circuit by changing the conductive status of an electron tube.

Other objects of the invention include the provision of:

A novel method and means to control conductivity of a gas-filled electron tube.

A novel circuit with impedance branches bridged by an electron tube to change the voltage distribution at points of the impedance branches when current flow in the tube is changed.

Electron valving means to valve control potentials to electrodes of a gas-filled tube to control shutting off and ignition of the tube.

Electron impedances arranged as voltage dividers to which electrodes of a gas-filled tube are connected, such impedances being varied by control potentials to govern operation of the gas-filled tube.

Parallel voltage dividers, at least one of which includes an electron impedance, between which the cathode and anode of a gas-filled tube are interposed, with the impedance being varied in value by a control potential to shut off the gas-filled tube.

Another general object of the invention is the provision of a novel method and means whereby a circuit may be varied in condition of stability under control of the circuit itself.

Further, an object of the invention is the provision of a circuit having alternate conditions of stability and in which the prevailing condition controls the effect of a control potential in bringing about the alternate condition.

Other objects of the invention include the provision of:

Means whereby concurrently activated firing and extinguishing controls for a gas-filled tube are limited to non-concurrent action upon the tube.

Means whereby firing and extinguishing control means for a gas-filled tube are made effective by successive pulses to successively fire and extinguish the tube.

Means whereby a single control pulse is effective either to fire or extinguish a gas-filled tube depending on whether the tube at the time the pulse is applied is in a non-conductive or conductive state, respectively.

2

Means whereby a single electron valve is operated to alternately fire and shut off a gas tube by successive control pulses.

Delay means whereby application to firing and extinguishing means, of a single control pulse or of concurrently applied control pulses, is prevented from effecting more than one change in the state of a gas tube.

Other objects of the invention will be pointed out in the following description and claims and illustrated in the accompanying drawing, which discloses, by way of example, the principle of the invention and the best mode, which has been contemplated, of applying that principle.

In the drawing:

Fig. 1 is a circuit diagram of an elemental form of the invention.

Fig. 2 is a circuit diagram of an advanced form of the invention, and

Fig. 3 is a circuit diagram of a modification of the form of invention shown in Fig. 2.

The circuits shown in Figs. 1 and 2 are similar to circuits included in my aforementioned copending application. For convenience, the parts of Figs. 1 and 2 will be given the same reference characters as similar parts of the circuits in the copending application.

Referring to Fig. 1 potential is continuously applied from a suitable D. C. source to plus and minus lines 1 and 2. Interposed between lines 1 and 2 are a plurality of parallel impedance sections comprised of voltage dividers. A first voltage divider comprises resistances 38 and parallel vacuum tubes 39a and 39b which may be

35 contained in a single envelope and which are provided with a common cathode. Tube 39a is a triode, while tube 39b is a multi-grid tube; specifically, a pentode. Connected to point 45 of said voltage divider is a resistance 43. Resistance 43 is tapped by a connection to the anode of gas-filled tube 55 which is of the three-element type. The cathode of this tube is connected to point 28 of a second voltage divider comprised of resistances designated 29 and 30.

40 The value of impedance 29 exceeds that of impedance 30 so that point 28 is relatively near the potential of line 2. When both of tubes 39a and 39b of the first voltage divider are at relatively high impedance, point 45 is relatively near the potential of line 1. In other words, under this condition, the impedance values are such that the potential difference between points 45 and 28 approaches that between lines 1 and 2 and supplies ionization potential for gas tube 55, but

50 the tube will remain shut off until its grid bias 55 is removed.

is reduced. It will be noted that the potential at point 28 is the cathode potential. The grid of gas triode 55 is connected via protective resistance 37 to a point 48 of a third voltage divider. This voltage divider comprises a resistance designated 40, a vacuum tube 42a, and a resistance 41. Resistance 41 is a self-biasing resistance for tube 42a and normally maintains relatively high grid bias for the tube, so that the tube impedance is high. Under this condition, the potential of point 48 is closer to that of line 2 than is the potential of point 28. Since point 28 is connected to the cathode of gas triode 55 and point 48 is connected to its grid, the potential difference between these points is the grid bias for the gas triode. Thus, under normal condition, with point 48 nearer than point 28 to the potential of minus line 2, the grid bias of the gas triode 55 is high, and it will remain extinguished. This third voltage divider—40, 42a, 41—constitutes a firing control section for the gas tube 55. When it is desired to fire the gas tube, positive potential from a suitable source is applied to a resistance 47 which is connected to the grid of vacuum tube 42a. As a result, the grid bias of the tube 42a is reduced, decreasing the impedance of the tube, so that current flow in the third voltage divider increases. Point 48 thereupon rises in potential sufficiently to reduce the grid bias of the gas tube 55 to the firing value. Since ionization potential also is being applied to the gas tube, the tube will fire and conduct current between points 45 and 28, respectively of the first and second voltage dividers. After ignition of the gas tube, its grid loses control. Hence, potential may be removed from resistance 47 to permit the impedance of the tube 42a to be increased.

With gas tube 55 now conductive, the electrical conditions at various points of the circuit are changed. The ignition of the tube 55 has, in effect, conductively connected points 45 and 28. Thus, there is increased current flow through resistors 38 and 30. The result is a rise in potential of point 28 and a drop in potential of point 45. The decreased potential of point 45 reduces the plate voltage of tubes 39a and 39b, further increasing their impedance. This reacts on the point 45 to raise its potential, compensating to some degree for its drop of potential resulting from conductivity of the gas triode 55. The net effect is that while the potential of point 28 has risen, the potential difference between points 45 and 28 is still high enough to maintain ionization of the gas triode. As long as gas tube 55 is conductive, there is grid current flow through resistances 37 and 41. The potential at point 48 rises, increasing the self-bias of tube 42a, so that impedance of this tube, with potential now removed from resistance 47, increases above its initial value. Accordingly, the potential at any point along resistance 40 will rise. In brief, with the gas triode 55 ignited, the potential at any point along resistor 38 falls to some extent, and the potential of points along resistors 40, 41, 29, and 30 rises. These changes may be utilized for control purposes. To illustrate, simply, the effect of conductivity of the gas tube 55, Fig. 1 shows in dotted lines a work magnet or relay R which may be connected by a switch S between the cathode of the gas tube and point 28. With the gas tube conductive, magnet R will be energized to perform a desired task.

The firing of the gas tube 55 has been explained. Briefly, a voltage divider comprised of

impedances 40, 42a, and 41, of which 42a is a vacuum tube, serves as a firing control. The firing control operates upon a change in the vacuum tube impedance 42a resulting from application of a control pulse or potential to its grid.

The first voltage divider, comprised of resistances 38 and parallel tubes 39a and 39b, acts as a selective extinguishing control for the gas tube 55. Each of the tubes 39a and 39b may be used to cause the gas tube to be extinguished. Positive potential applied to a resistance 44 will oppose negative potential applied by a battery 44a to the grid of tube 39a. The grid bias of tube 39a will thereupon be lowered, increasing current flow through resistance 38 and this tube, as a result of which the potential at point 45 falls. The constants of this first voltage divider are such that the potential applied to resistance 44 will cause an amplified drop in potential of point 45. The decreased potential of this point reduces the potential on the anode of gas tube 55 below the ionization potential. Consequently, the gas tube is extinguished.

When it is desired to extinguish the gas tube 55 under control of tube 39b, a switch 10 is opened. This places a resistance 224 in series with resistances 204 and 206 of a fourth voltage divider, so that the potential of a point 212 is raised. The point 212 is connected via a switch 12 to the screen grid of tube 39b. Now, with the point 212 at increased potential, the screen potential of tube 39b is high enough to enable a reduction in its control grid bias to be effective. Such reduction in control grid bias takes place upon application of positive potential to a resistance 235c. The pulse on 235c counteracts the effect of a battery 236 on the control grid of tube 39b, reducing its grid bias. The increased conductivity of tube 39b has the same effect as the increased conductivity of tube 39a in reducing the potential at point 45 and causing the gas tube 55 to be extinguished.

Pulses may be applied at successive times from different sources to resistances 44 and 235c to cause tubes 39a and 39b to serve successively as extinguishing controls for the gas tube. Also, tube 39b may be rendered ineffective to serve as extinguishing control by lowering its screen potential either through the shifting of switch 12 or the closing of switch 10. Selective means are thus provided for acting singly or in succession to control extinction of the arc in the gas tube 55.

It will be understood that the firing control tube 42a may serve as an amplifier or merely as a pulse-valving device, depending on whether it is or is not desired to amplify the pulse appearing on resistance 47.

Fig. 2 shows another form of the invention which presents certain advances over the form shown in Fig. 1. Similarly to the Fig. 1 circuit, the circuit of Fig. 2 includes voltage dividers which have vacuum tubes varied in impedance by control pulses to fire and extinguish a gas tube. As with the Fig. 1 circuit, the firing of the gas tube in the Fig. 2 circuit changes the electrical condition of various points of the circuit. An additional feature of the Fig. 2 circuit involves means whereby concurrently pulsed firing and extinguishing controls nevertheless are caused to act singly; i. e., either the firing or extinguishing control is rendered effective at any one time. Another feature of the Fig. 2 circuit is means whereby the status of the circuit itself, which is dependent on the status of the gas triode, determines which of the concurrently pulsed firing and

extinguishing controls is to be effective. As will be pointed out, the gas triode when conductive enables a control potential to act through the extinguishing control to render the gas triode non-conductive, while the gas tube when extinguished enables control potential to act through a firing control to ignite the gas tube. Another feature of the Fig. 2 circuit is delay means whereby a single pulse, or concurrent pulses, will cause only one reversal of the status of the circuit; i. e., of the status of the gas tube.

In detail, Fig. 2 has a plus and minus lines 1 and 2 to which potential is applied from a direct current source. Three voltage dividers are across the lines 1 and 2. The first voltage divider comprises a resistance 127 and pentode vacuum tube 128b. These elements are similar to the resistance 38 and tube 39b of the Fig. 1 circuit. A second voltage divider comprises resistances 120, 121, and 122 and a condenser 123 shunting resistance 122. The gas tube 129 is interposed between the first and second voltage dividers. Thus, the point 134 of the first voltage divider is connected to a current limiting resistor 130 tapped by a connection to the anode of the gas triode 129, while the cathode of the gas triode is connected to the point 135 of the second voltage divider. The firing control includes a third voltage divider comprised of resistances 124, tube 125a and resistance 126. These elements of the third voltage divider are similar to elements 40, 42a, and 48 of the firing control section of the Fig. 1 circuit.

With tube 128b at high impedance, point 134 is near the potential of line 1. The relation of the resistances 120, 121, and 122 is such that point 135 is near the potential of line 2. Therefore, the potential difference between points 134 and 135 approaches that between lines 1 and 2 and is sufficient to apply ionization potential to the gas tube, the tube, however, remaining shut off until its grid bias is reduced. The grid of the gas tube is connected via a variable resistance 131 to the point 136 of the third voltage divider. Resistance 126 is a self-biasing control for tube 125a and maintains the tube at normally high impedance. Under this condition, point 136 is nearer than point 135 to the potential of line 2 and the grid bias of gas tube 129 is relatively high. Upon application of a positive potential to resistor 144, the grid bias of tube 125a is reduced, decreasing the impedance of the tube, so that point 136 rises in potential. As a result, the grid bias of gas tube 129 is lowered to the firing point.

When the tube 129 is conductive, there is increased current flow through resistances 127 and 122. There is also grid current flow through resistances 131 and 126. The increased current flow through resistance 127 lowers the potential at point 134. The increased current flow in resistance 122 produces a rise in the potential of points 143 and 135. The changes in potentials of points 134 and 135 do not, however, reduce the potential difference between them below the required ionization potential for the gas tube 129. The rise in potential of point 143 increases the screen grid potential of the tube 128b. Tube 128b thereby is prepared for a material change in impedance upon reduction of its control grid bias. The reduction of control grid bias of the tube 128b is effected upon application of a positive pulse to resistance 132 which counteracts the effect of the battery 133. Upon reduction of the grid bias of tube 128b, its impedance is lowered,

causing point 134 to drop in potential to an extent such as to cause the gas triode to be extinguished. Tube 128b, therefore, serves as an extinguishing control in the same manner as explained for tube 39b of Fig. 1.

The changes in potential at various points of Fig. 2 circuit may be utilized for control purposes in the same manner as the potential changes in the Fig. 1 circuit. In addition, one control purpose in the Fig. 2 circuit is to self-condition the circuit, as a result of ignition of the gas tube, so as to prepare the gas tube to be shut off.

Resistors 132 and 144 may be connected, as indicated by the dotted line 400 to a single pulse source. In that event, both resistances 132 and 144 will be pulsed simultaneously from a common source and are equivalent to a single resistor tapped by connections to the grids of tubes 125a and 128b. On the other hand, resistances 132 and 144 may be pulsed concurrently from separate sources.

With resistances 132 and 144 pulsed simultaneously, the firing and extinguishing controls tend to act concurrently and counteract each other. However, when the gas tube is extinguished, concurrent pulsing of the firing and extinguishing controls will first take effect upon the firing control since the screen voltage of the extinguishing control tube 128b is now at the lower of two values. The firing of the gas tube 129 causes the potential at point 143 to rise, but this rise is exponential owing to the presence of the condenser 123. The action of the condenser delays the rise in voltage of point 143 to prevent the screen potential of the pentode 128b from increasing to an effective value until after the pulsing interval. Thus, tube 128b remains at high impedance, and point 134 at relatively high potential, until after the pulsing interval in which the gas tube was fired. Accordingly, the gas tube 129 will not be re-extinguished in the same pulsing interval in which it was fired. Thus, delay means are provided whereby when the gas tube is shut off, pulses concurrently applied to the firing and extinguishing controls are effective only to ignite the gas tube.

The delay means, comprising condenser 123, also serves for preventing the gas tube from being extinguished and re-fired during the same pulsing interval. Assuming the gas tube to be in a conductive state, point 143 is at high potential, so that the screen of tube 128b is maintained at high voltage. Thus, the next pulse applied to resistance 132 will be effective to reduce the impedance of tube 128b to such extent as to reduce the potential at point 134 below ionization potential. Accordingly, tube 129 will be extinguished. The decrease in potential of point 134 resulting from increased current flow in tube 128b will be counteracted to some extent by the rise in potential of this point consequent upon the shutting off of the gas tube 129. Should points 143 and 135 drop instantly to their lower potentials upon the shutting off of the gas tube, the screen voltage of tube 128b will be lowered by the potential fall of point 143 to such extent that point 134 will rise to ionization potential while the pulses are still acting concurrently on resistances 132 and 144. Also, the decreased potential of point 135 and the increased potential on the grid of the gas tube resulting from the pulse applied to resistance 144 will produce a reduced grid bias for the gas tube sufficient to re-fire the gas tube. The condenser 123, however,

serves to delay the fall in potential of points 135 and 143 upon the shutting off of the gas tube. As soon as points 143 and 135 begin to drop in potential, condenser 123 which has been charged up to the potential obtaining between point 135 and line 2, commences to discharge through resistor 122. The discharge of the condenser tends to hold the points 135 and 143 at high potential. Accordingly, the screen voltage of tube 128b tends to remain high, so that its impedance will continue low and point 134 will be maintained below ionization potential. Further, the maintained high potential of point 135 counteracts the rise in potential of the grid of the gas tube which results from the pulse applied to the resistance 144 concurrent with the pulse on resistance 132. In other words, the discharge of the condenser serves to maintain a difference in potential between points 135 and 136 which is sufficient to prevent ignition of the gas tube even though a pulse is being applied to resistance 144.

The time taken for points 135 and 143 to drop in potential when the gas tube is extinguished is determined by the time constant of resistance 122 and the condenser 123 and is such as to delay the drop of potential of these points exponentially until after the pulsing interval. The net result is that when the tube 129 is extinguished by a pulse on resistance 132, the points 143 and 135 will be maintained at increased potential and the point 134 at lowered potential at least for as long as the pulses are acting concurrently on resistances 132 and 144. In other words, the gas tube will be held at low anode potential and high grid bias until after the shut-off pulse has ceased to act.

The foregoing has described a method and means for alternately firing and extinguishing a gas tube during successive pulsing intervals, in each of which a firing control and an extinguishing control are concurrently pulsed. As pointed out the Fig. 2 circuit has alternative conditions, and is self-governing so that when in either of these conditions, it enables control pulses or a pulse to reverse the condition. In other words, the condition of the circuit itself determines in which direction the condition of the circuit will be changed. Further, it has been explained that the gas tube when conductive will allow a pulse to shut off the tube and, when shut off, will allow a pulse to ignite the tube. Thus, successive pulses will alternately fire and extinguish a gas tube under control of the tube itself. In the Fig. 2 circuit, the pulses or pulse were concurrently applied to two voltage dividers, one serving as a firing control for a gas tube and the other as the extinguishing control.

Fig. 3 shows a modification in which a single vacuum tube serves both as extinguishing and firing control means and in which the grid of the gas tube remains at fixed potential while the cathode potential is reduced to cause ignition.

In detail, 501 and 502 designate the plus and minus D. C. source lines. Between these lines is a first voltage divider comprised of resistance 503 and pentode 505. The point 504 of this voltage divider connects via variable resistance 508 to the anode of gas-filled tube 509. The cathode of this gas tube is connected to point 516 of a second voltage divider, comprised of resistances 514, 515, 517, and condenser 518 which shunts resistance 517. The grid of gas tube 509 is connected via variable resistance 510 to a point 512 of a third voltage divider comprising resistances 511 and 513.

As in the two previous embodiments, the values of the impedances are so related that, with tube 505 at high impedance, point 504 is relatively near the potential of line 501 and point 516 is nearer line 502 in potential. The difference in potential between points 504 and 516 furnishes ionization potential for gas tube 509.

The values of the resistances of the second and third voltage dividers are so related that point 512 normally is closer than point 516 to the potential of line 502. The difference in potential between points 512 and 516 is the grid bias for the gas tube and normally is of sufficient magnitude to prevent ignition of the gas tube.

The screen grid of tube 505 is connected to a point 520 of the second voltage divider. When gas triode 508 is in non-conductive condition, the potential at point 520 is at the lower of two possible values for this point. Accordingly, when the gas triode is in an extinguished status, the screen potential of the pentode 505 is at a relatively low value. The control grid of tube 505 is connected to a bias battery 506 which has a connection to a resistor 507 for receiving pulses from a suitable source. It may be mentioned that, assuming the circuit constants to be substantially the same as in Fig. 2, the potential of pulses applied to resistor 507 of Fig. 3 should be higher than that of a pulse or pulses applied to the resistors 132 and 144 of Fig. 2.

Assume that gas triode 509 is extinguished, and a positive pulse is applied to resistor 507. Such pulse opposes bias battery 506, reducing the control grid bias of tube 505. In view of the relatively low screen potential of the tube 505, the reduction of the control grid bias of this tube causes only a slight current rise through the voltage divider comprised of resistance 503 and the tube. This slight rise in current tends to reduce the potential at point 504 slightly. However, a second, controlling result of the decrease in grid bias of the tube 505 is an increase in screen grid current flow of this tube. As a result, point 520 is brought nearer line 502 in potential. One effect of this is a lower screen potential for tube 505, so that its impedance increases, tending to maintain point 504 at its initial higher potential which it had before the pulse was applied to resistor 507. A second and principal effect of the lowered potential of point 520 is a reduction in current flow through resistors 515 and 517. Consequently, point 516 approaches closer to the potential of line 502. One result of such fall in potential of point 516 is that the potential difference between this point and point 504 increases; i. e., the anode potential of gas triode 509 increases. A second result of the drop in potential at point 516 is that the potential difference between this point and the point 512 of the third voltage divider is reduced; i. e., the grid bias of the gas triode 509 is decreased. The cumulative effect of the increase in anode potential and decrease of grid bias of the gas tube 509 is that the tube is ignited. After the tube is ignited, the control potential or pulse may cease to act on the resistor 507.

As in the other embodiments, with the gas triode in a conductive state, points 520 and 516 rise in potential, and such change may be utilized for control purposes. The change in potential at point 520 serves also to determine that the next pulse applied to resistor 507 shall extinguish the gas tube 509. Thus, with point 520 at the higher of its two possible potentials, the screen potential of pentode 505 is also relatively high. It

should be noted that the higher potential at point 516, obtaining while the gas tube is in conductive condition, increases the grid bias of the gas tube above the critical value. This has no effect now, however, on the conductivity of the gas tube since the grid of the tube loses control when the tube is ignited. Assume, now, that it is desired to extinguish the gas tube 509. A pulse is again applied to resistor 507, reducing the control grid bias of the pentode. The two now concurrently operating factors, high screen potential and reduced grid bias of the pentode 505, combine to materially reduce its impedance. The resulting increase in current flow through resistance 503 and pentode 505 causes point 504 to drop in potential to an amplified extent with respect to the potential of the control pulse applied to resistor 507. With point 504 at the lowered potential, insufficient potential difference prevails between the anode and cathode of the gas tube 509 to enable the tube to remain conductive. Accordingly, the gas tube is extinguished.

Condenser 518 in Fig. 3 has the same function as condenser 123 in Fig. 2. Briefly, it maintains point 520 at the higher potential, after the gas tube is extinguished, until after the shut-off pulse has ceased to act. Secondly, it maintains point 516 at the higher potential until after the shut-off pulse has ceased to act, thereby maintaining the grid bias of the gas tube 509 sufficiently high to prevent ionization or re-ignition. When, following extinction of the arc in the gas tube by one control pulse, a next such pulse will fire the gas tube by causing a reduction in potential at point 516 and, hence, of the cathode potential, in the manner described. The condenser 123 will maintain point 516 at lowered cathode potential and point 520 at lowered screen controlling potential until after the firing pulse has ceased to act.

The foregoing has described a method and means of firing and shutting off a gas triode by a pulse applied to a common point of the circuit and to only one circuit element; namely, a single variable impedance comprised of a vacuum tube serving as part of a voltage divider. This single element of the circuit, in response to successive pulses applied at a common point, will cause alternate firing and shutting off the gas triode. The determination of whether the single element shall respond to the pulse for firing the gas tube or for extinguishing the gas tube is made by the circuit itself in accordance with the prevailing status of the gas tube. Thus, with the gas tube conductive, the single element will utilize the control pulse as an extinguishing pulse. On the other hand, with the gas tube in non-conductive state, the single element will apply the control pulse as a firing pulse. The voltage divider including resistance 503 and tube 505 serves as a combined firing and extinguishing control means for the gas tube. It will be noted, further, that the control pulse is effective, when the gas triode is extinguished, to increase the potential between anode and cathode of the gas triode and concurrently decrease its grid bias so as to cause ignition. Further, it will be noted that the grid potential of the gas tube remains substantially fixed and its grid bias is varied by changing the potential of the cathode.

While there have been shown and described and pointed out the fundamental novel features of the invention as applied to several embodiments, it will be understood that various omissions and substitutions and changes in the form and de-

tails of the devices illustrated and in their operation may be made by those skilled in the art, without departing from the spirit of the invention. It is the intention, therefore, to be limited only as indicated by the scope of the following claims.

What is claimed is:

1. An electrical system comprising a power source, parallel voltage dividers connected thereto, a gas-filled electron tube including anode, cathode, and grid electrodes and having the anode and cathode connected to points of two said dividers to bridge them conductively when ignited, said points being so chosen that cathode potential is lower than anode potential and higher than grid potential, said tube being ignited upon a reduction in potential difference between cathode and grid and upon such ignition reducing the anode potential and increasing the cathode potential, and means responsive to an electrical pulse for further reducing the potential at the anode-connected point to such extent as to deprive the anode of the potential required to maintain the tube ignited, whereupon the tube is extinguished.
2. An electrical system as in claim 1, and pulse responsive means comprising an electronic discharge tube in the voltage divider to a point of which the anode of the gas-filled tube is connected, said discharge tube upon application of a pulse thereto being reduced in impedance and thereby causing current flow in the latter voltage divider to increase and reduce the potential at the anode-connected point below the value required to sustain ignition of the gas-filled tube.
3. An electrical system comprising a power source, and an electrical network connected to said source and including parallel voltage dividers and a gas tube bridging said dividers, said tube including an anode electrode connected to a point of a first one of said dividers and a cathode electrode connected to a point of a second one of said dividers and a control grid electrode at lower potential than the cathode potential, the difference in potential between cathode and grid electrodes being reduced by utilizing an electrical pulse to change the potential of one of the latter electrodes whereby the tube is ignited, said first voltage divider including a variable impedance electronic discharge device reduced in impedance by an applied potential so as to increase current flow in the first voltage divider and thereby lower the potential at the anode-connected point below the value necessary to sustain ignition of the gas tube.
4. An electrical system comprising a power source, and an electrical circuit network connected to said source and including parallel voltage dividers and a gas tube including an anode connected to a point of a first one of said dividers and a cathode connected to a point of a second one of said dividers and also including a control grid normally at such bias as to prevent ignition of the tube, means for reducing the grid bias so as to ignite the tube, whereby the distribution of electrical values about the network is changed in such manner as to reduce the potential at the anode-connected point and increase the potential at the cathode-connected point, and means responsive to an electrical pulse for further reducing the potential at the anode-connected point to such extent as to lower the anode potential below a critical ignition-sustaining value, so that the tube is extinguished to es-

tablish an alternative distribution of electrical values about the network.

5. An electrical system comprising a power source, and an electrical circuit network connected thereto and including parallel voltage dividers and a trigger tube having an anode and cathode and control grid, a connection from the anode tapping a chosen point of a first one of said dividers and a connection from the cathode tapping a chosen point of a second one of said dividers, said dividers being so proportioned and the points so chosen as to provide potential difference between the anode and cathode sufficient to enable the tube to be triggered to a conductive state upon reduction of the cathode-to-grid potential, means whereby such reduction is effected, and means responsive to an electrical signal for increasing current flow in the first divider so as to reduce the potential at the tapped point thereof sufficiently to cause the tube to trigger back to a non-conductive state.

6. An electrical system comprising a power source, and a circuit network connected thereto and including parallel voltage dividers and a gas tube bridging the dividers, with an anode connected to a point of a first one of said dividers and a cathode connected to a point of a second one of said dividers, said points being so chosen as to provide sufficient anode-to-cathode potential to maintain an arc in the tube after such arc has been started, said tube including a starting grid normally below cathode potential, means for receiving electrical pulses and responding to one said pulse to reduce the potential difference between cathode and grid sufficiently to start an arc in the tube and responding to another pulse of the same polarity for reducing anode to cathode potential below arc-sustaining value, whereby the tube is alternated in condition by successive pulses of the same polarity.

7. An electrical system comprising a power source, and an electrical circuit network connected to said source and including parallel voltage dividers and a trigger tube interposed between said dividers so as to establish certain electrical values about the network when in triggered state and other electrical values when in reverse state, said tube including an anode, cathode, and grid of which the anode and cathode are respectively connected to points of a first one of said voltage dividers and second one of said dividers so chosen as to apply sufficient anode to cathode potential to enable the tube to be tripped to triggered state by reduction of grid bias and to maintain the tube in such state while the first mentioned electrical values prevail about the network, and means receiving an electrical pulse for reducing the potential at said point of the first divider to an extent depriving the anode of sufficient potential to maintain the tube in triggered state, whereupon the tube trips to reverse state and establishes said other electrical values about the network.

8. An electrical system comprising current supply lines and a circuit network supplied by said lines and including three parallel voltage dividers, a trigger tube having an anode connected to a point of a first one of said dividers to derive anode potential therefrom and having a cathode and control grid connected respectively to points of a second one of said dividers and third one of said dividers, means impressing a control potential upon the circuit network to react on one of the latter two dividers to reduce the po-

tential difference between the grid and cathode to an extent such as to trip the tube from a non-conductive state to a conductive state, and means for reducing the potential at said point of the first divider to an extent such as to lower the anode potential below a value required to maintain the tube conductive, whereby the tube trips to its non-conductive state.

9. An electrical system comprising a power source and an electrical network connected thereto and including a pair of parallel voltage dividers and a gas-filled trigger tube bridging points of said dividers, one of said dividers including parallel variable impedance electronic discharge devices, either of which upon a change in its impedance alters the potential at said point of the latter divider to such extent as to change the status of the tube, and means for rendering said discharge devices selectively effective, in response to electrical pulses applied thereto, to thus alter the potential at said point of the latter divider.

10. An electrical system comprising a power source, and an electrical network connected thereto and including parallel voltage dividers and a gaseous discharge tube bridging said dividers, with an anode connected to a point of one said divider and a cathode to a point of another said divider, said tube also having a control grid normally biased to prevent ignition of the tube and reduced in bias to cause ignition of the tube, said tube upon being ignited changing the distribution of electrical values about said network, a variable impedance electronic discharge device prepared by such change for responding to an electrical pulse to reduce the anode to cathode potential of the gaseous discharge tube below ignition-sustaining value, and means for applying said pulse to said discharge device to effect its response, after being prepared therefor, so as to reduce the anode to cathode potential below ignition-sustaining value for the gaseous discharge tube.

11. A circuit comprising a pair of impedance branches, a gas-filled tube bridging said branches and including a control grid, one said branch including a variable impedance electronic discharge device, the constants of said circuit being so adjusted that upon an alteration in impedance of the discharge device the tube is quenched, means for applying potential to said grid tending to ignite the tube and concurrently applying potential to said discharge device tending to quench the tube, and means controlled by the electrical condition of the circuit itself, and including delay means, for rendering only the discharge device or the grid effective to act in response to the concurrently applied potential to effect its function.

12. A self-governing circuit comprising a pair of impedance branches, a gaseous discharge tube bridging said branches and including a control grid, one said branch including a variable impedance electronic discharge device effective upon reduction of its impedance to quench the tube, means for applying potential to the discharge device tending to reduce its impedance and quench the tube and concurrently applying potential to the control grid tending to ignite the tube, and means controlled by the tube itself, and including delay means, for selectively rendering the potential effective when the tube is in a non-conductive status to act through said grid to ignite the tube and effective when the tube is in conductive status to act through said discharge device to extinguish the tube.

13. An electrical system comprising a power

source and an electrical network connected thereto and including parallel impedance branches and a gaseous discharge tube bridging said impedance branches and effective when in a conductive state to produce a desired potential at a point of one said impedance branch, a variable impedance electronic discharge device including a control electrode connected to a pulse applying means and another control electrode deriving potential from said point and effective when said point is at said desired potential to enable the pulse applied to the first electrode to effectively change the impedance of the device, said device being so connected into the network as to extinguish the tube upon said change in impedance.

14. A circuit comprising current supply lines, a gas-filled trigger tube including anode, cathode, and grid electrodes, means so connecting the electrodes to the supply lines as normally to provide sufficient anode-cathode ionization potential and cathode-grid potential above tripping value, a variable impedance electronic discharge tube so connected into the circuit and to said gas-filled tube as to be effective in response to a first electrical pulse to reduce the cathode-grid potential and trip the tube to ionized state and in response to a following pulse to reduce anode-cathode potential to quench the tube, and means for applying said pulses successively to the electronic discharge tube so as to effect such successive alternations in the status of the gas-filled tube.

15. A circuit comprising current supply lines, an impedance bridging said lines, and means for alternately increasing and reducing potential at a point of said impedance comprising a single variable impedance electronic discharge tube having anode and cathode electrodes connected to said lines and including a screen grid connected to said point and also including a control grid, means for applying successive pulses of the same polarity to said control grid, one such pulse being effective when the screen grid is at high potential to materially increase current flow in the tube and another such pulse being effective when the screen grid is at low potential for increasing screen grid current flow, and means responsive to the increase in current flow of the tube for reducing the potential at said point and responsive to the increased screen grid current flow for increasing the potential at said point, whereby successive pulses of the same polarity applied to said control grid effect successive opposite changes in potential at said point.

16. A circuit network comprising a gas filled trigger tube including an anode and a cathode, a variable impedance electronic tube including an anode, cathode and a plurality of control electrodes, means connecting the anode of the variable impedance tube to the anode of the trigger tube, means connecting a first one of said electrodes to the cathode of the trigger tube, means for applying successive pulses of the same polarity to the second one of said electrodes, one of said pulses reacting upon the first electrode to reduce its potential and thereby to reduce the cathode potential of the trigger tube sufficiently to cause its ignition, said trigger tube upon ignition increasing the potential of the first elec-

trode whereby a succeeding one of said pulses by reason of the higher potential of the first electrode sufficiently reduces the impedance of the variable impedance electronic tube to thereby reduce the anode potential of the trigger tube sufficiently to extinguish the trigger tube.

17. A circuit comprising a gas-filled electronic trigger tube including anode, cathode, and grid electrodes, a variable impedance electronic discharge tube, means electrically connecting the discharge tube into the anode-cathode circuit of the trigger tube so as to quench the trigger tube upon a change in impedance of the discharge tube, said discharge tube including a control electrode connected to the output of the trigger tube and varying in potential in accordance with the quenched or ignited status of the trigger tube, and control means in the discharge tube responsive to successive electrical pulses for cooperating with the control electrode when the trigger tube is in quenched state to reduce the cathode-grid potential of the trigger tube to effect its ignition and for cooperating with the control electrode when the tube is in ignited status for effecting said change in impedance of the discharge tube so as to quench the trigger tube, whereby the trigger tube is alternately ignited and quenched, under control of the trigger tube itself, by successive pulses applied to the control means of the discharge tube.

18. In combination, a gaseous discharge device with an anode and a cathode and a grid, a first electron emission device, a power source therefor, means for adjusting the electronic flow from said source through said emission device, means conductively connecting said cathode to said power source, means connecting said anode and said electron emission device so that anode potential is altered upon adjustment of said electronic flow, a second electron emission device connected to said source, means for altering electronic flow from said source through the second emission device, means conductively connecting said grid and the second emission device so that grid potential is altered upon adjustment of electronic flow through the second emission device, said gaseous discharge device being ignited upon said alteration of the grid potential and quenched upon said alteration of the anode potential.

19. An electrical flip-flop circuit including a plurality of resistors forming a voltage divider, a plurality of impedances including an electron emission device forming a second voltage divider, means electrically connecting said electron emission device to said first divider, a gaseous discharge device, means electrically connecting said gaseous discharge device to each of said voltage dividers, control means to which successive voltage impulses are applied, and means, including said electronic device and a condenser shunting one of said resistors, for alternately igniting and quenching said discharge device upon successive applications of voltage impulses to said control means whereby said desired potential is produced only upon each second application of said potential.

ARTHUR H. DICKINSON.
